UNITED STATES PATENT OFFICE.

LIVY DICK MURPHY, OF KANSAS CITY, MISSOURI, ASSIGNOR OF ONE-
THIRD TO CHARLES E. McCLURE, OF SAME PLACE.

BAYONET.

SPECIFICATION forming part of Letters Patent No. 673,527, dated May 7, 1901.

Application filed January 14, 1901. Serial No. 43,258. (No model.)

To all whom it may concern:

Be it known that I, LIVY DICK MURPHY, a citizen of the United States, and a resident of Kansas City, in the county of Jackson and State of Missouri, have invented new and useful Improvements in Bayonets, of which the following is a specification.

My invention relates to bayonets and improved means for securing the bayonet to the muzzle of a firearm; and the object of my invention is to produce a disappearing bayonet which may be quickly and easily withdrawn into a recess under the muzzle and which will be invisible when in that position and having no unsightly projections either when so withdrawn or in use.

With this object in view my invention consists in the novel construction and arrangement of parts hereinafter described and claimed, and illustrated in the accompanying drawings, in which—

Figure 1 is a side elevation of the muzzle of a rifle provided with a bayonet in extended position constructed in accordance with my invention. Fig. 2 is a side elevation of the muzzle, the bayonet being retracted. Fig. 3 is a top plan view showing the bayonet partly extended. Fig. 4 is an enlarged transverse sectional view taken on a line *a b* of Fig. 1.

In the fore-stock 2, just below the barrel 3, I form a longitudinal groove of sufficient length to receive the bayonet 4. The bayonet is approximately triangular in cross-section and is concaved on its face adjacent to the barrel, as shown in Fig. 4.

The means for extending or withdrawing the bayonet comprises a cross-key 5, passing through a slot in the bayonet, and a slidable band or sleeve 6, embracing the fore-stock and barrel. The ends of the key 5 extend, respectively, through two longitudinal slots 7, formed in the fore-stock 2 just below the lowest part of the barrel 3. The extreme ends of the key 5 lie in slots in the band 6. One end of the key is provided with a head 8, by which the key may be removed from the fore-stock when it is necessary to remove the bayonet entirely.

When the bayonet is extended, as shown in Fig. 1, it is held in that position by two spring-

detents 9, which are secured to opposite sides of the fore-stock 2 and have shoulders which engage the rear edge of the sleeve 6. The bayonet is withdrawn by pressing the detents 9 inwardly or together with the thumb and 55 finger and sliding the sleeve 6 back to the position shown in Fig. 2.

10 designates a ramrod, and 12 designates a band embracing the end of the ramrod and the muzzle of the rifle. 60

Having now fully described my invention, what I claim as new, and desire to secure by Letters Patent of the United States, is—

1. In a firearm, the combination of the stock having a longitudinal recess therein adjacent to the muzzle, and having a longitudinal slot therein, opening into said recess, a bayonet sheathed in said recess, and a transverse key passing through the butt of the bayonet and through said slot; substantially as described. 70

2. In a firearm, the combination of the stock having a longitudinal recess therein adjacent to the muzzle and having a longitudinal slot therein opening into said recess, a bayonet sheathed in said recess, a transverse key passing through the butt of the bayonet and projecting through said slot, and a slideable sleeve or band embracing the stock and muzzle and having a slot therein for the end of said key, whereby moving said sleeve moves the bayonet, substantially as described. 80

3. In a firearm, the combination of the stock having a longitudinal recess therein adjacent to the muzzle, and having a longitudinal slot therein opening into said recess, a bayonet sheathed in said recess, a transverse key passing through the butt of the bayonet and extending through said slot, a slideable sleeve or band embracing the muzzle and stock and having a slot for engaging one end of said key, and a spring-detent secured to the stock for locking said sleeve and the bayonet in extended position, substantially as described. 90

In testimony whereof I affix my signature in the presence of two witnesses.

LIVY DICK MURPHY.
